INVENTOR-
Edwin W. Smith

UNITED STATES PATENT OFFICE.

EDWIN W. SMITH, OF BEVERLY, MASSACHUSETTS, ASSIGNOR, BY MESNE ASSIGNMENTS,
TO UNITED SHOE MACHINERY CORPORATION, OF PATERSON, NEW JERSEY, A COR-
PORATION OF NEW JERSEY.

RETAINING DEVICE.

1,276,981.

Specification of Letters Patent. Patented Aug. 27, 1918.

Application filed September 27, 1917. Serial No. 193,557.

To all whom it may concern:

Be it known that I, EDWIN W. SMITH, a citizen of the United States, residing at Beverly, in the county of Essex and State 5 of Massachusetts, have invented certain Improvements in Retaining Devices, of which the following description, in connection with the accompanying drawings, is a specification, like reference characters on the drawings indicating like parts in the several figures.

This invention relates to retaining devices and particularly to those for removably holding a member in place upon a 15 spindle or the like.

In many classes of machines, a ribbon or band of material to be operated upon is supplied to the operating mechanism from a continuous coil carried by a core or roll 20 rotatable about a spindle and from which the material is drawn in the operation of the machine. It is, of course, necessary at intervals to supply to the apparatus a new coil, and to give the proper feed of material the ribbon is drawn off against a certain resistance, this ordinarily being furnished by pressing one end of the roll or coil against a yieldable friction surface by means of an adjustable abutment or retaining 25 device at the opposite end. To enable these results to be attained satisfactorily, the retaining device must be readily removable from the spindle and when in place must hold the roll firmly against the pressure exerted by the friction device. To furnish a simple and easily operated retaining 30 device possessing such characteristics is the object of the present invention.

A feature of my improved retaining device 40 consists of a collar movable upon a spindle for coöperation with a member on the spindle, such as a supply roll, this collar carrying a member provided with an opening to receive and normally engage the spindle to retain the collar in place.

Another feature of the invention concerns the manner in which the engaging member coöperates with the spindle, so that it may be easily moved in one direction while resisting movement in the other. In the form illustrated the engaging member from the point at which it is secured is inclined with respect to the spindle.

As a further feature, the invention pro-

vides the engaging member with a portion 55 which may be readily manipulated by the operator to disengage the retaining device for movement along the spindle away from the roll.

For an understanding of the invention, 60 reference may be had to the accompanying drawing, in which—

Figure 1 shows the device applied to a stamping machine, said device itself appearing in end elevation, and

Fig. 2 is a front elevation of the supply roll and retaining device.

One of a number of utilizations of my invention is in connection with the color ribbon of a stamping machine, and I have 70 shown at 10 a portion of such an apparatus. The supply spindle 12 of the machine carries upon a roll 14 a coil of ribbon R, one extremity of which roll contacts with a friction device including a collar 16 fixed 75 to the spindle by a screw 18, and a spiral spring 20 surrounding the spindle, with one end against the collar and the opposite end forcing a washer 22 against the end of the roll 14. The roll may be applied to or removed from the spindle over its free end 24, it being retained thereon against the washer 22 by an abutment consisting of a collar 26 having at its outer side an enlarged head 28, which is preferably knurled 85 to enable it to be firmly grasped by the operator. This collar so fits the spindle as to be freely movable thereon. Adjacent to the edge of the head 28 is an opening adapted to receive a screw 30 which secures to the 90 outer face of the head a resilient member, here shown as a leaf spring 32. In this spring is an opening 34 to permit the passage of the spindle. The securing point of the spring to the head and the opening 34 95 are so related and the spring is so tensioned, that when the collar is upon the spindle the edge of the opening 34 toward the securing point is forced into engagement with the spindle. At this time, by 100 the contact of the spring and spindle, the former is held inclined to the outer face of the head, it diverging therefrom toward the free end of the spring. As a result of this, when the collar 26 is applied to the spindle 105 and moved toward the roll 14, the tendency of the contact of the spring with the spindle is to lift it out of engagement therewith so

that the collar may be moved without much resistance toward the roll. Movement in the opposite direction, however, tends to press the spring toward the head and therefore brings it into firmer engagement with the spindle, thus locking the collar in place holding it at any point to which it may be adjusted against the expansive force of the spring 20. To permit the spring 32 to be readily raised out of contact with the spindle so that the collar may be adjusted toward the free end of the spindle or removed therefrom, said spring has an end portion 36 which is carried over the edge of the head and inwardly at the side of said head adjacent to the body of the collar. By grasping the head and this spring portion 36 between the thumb and forefinger, the operator can move the spring away from the head and thus destroy its clutching effect.

Having thus described my invention, what I claim as new and desire to secure by Letters Patent of the United States is:

25 1. A device for retaining a member in place upon a spindle comprising a collar for coöperation with the member, said collar being freely movable upon the spindle, and a resilient member carried by the collar and 30 being provided with an opening to receive the spindle, the edge of the opening being held normally in engagement with the spindle to retain the collar against movement thereon.

35 2. A device for retaining a member in place upon a spindle comprising a collar for coöperation with the member, said collar being movable upon the spindle, and a resilient member carried by the collar and 40 being provided with an opening to receive the spindle, the member being so tensioned as to tend to move toward the collar to hold the edge of its opening normally in engagement with the spindle and having a portion 45 upon the opposite side of the collar by which it may be actuated to disengage it from the spindle.

3. A device for retaining a member in place upon a spindle comprising a collar 50 for coöperation with the member, said col-

lar being movable upon the spindle, and a leaf spring secured at one end adjacent to the edge of the outer face of the collar and being provided with an opening through which the spindle projects, the spring being tensioned and positioned to hold the edge of the opening in normal engagement with the spindle. 55

4. A device for retaining a member in place upon a spindle comprising a collar for 60 coöperation with the member, said collar being movable upon the spindle and having an enlarged head at its outer side, and a leaf spring secured at one end adjacent to the edge of the outer face of the head and 65 being provided with an opening to receive the spindle, the spring being tensioned and positioned to hold the edge of the opening in normal engagement with the spindle and having a portion extending over the 70 edge of the head to the opposite side thereof to enable the spring to be grasped and moved outwardly and upwardly to disengage it from the spindle.

5. A device for retaining a member in 75 place upon a spindle comprising a collar for coöperation with the member, said collar being freely movable upon the spindle, and a resilient member carried by the collar and 80 being provided with an opening to receive the spindle, the edge of the opening being held normally in engagement with the spindle and with the resilient member inclined with respect to said spindle.

6. A device for retaining a member in 85 place upon a spindle, comprising a collar for coöperation with the member, said collar being movable upon the spindle, and a leaf spring secured at one end adjacent to the edge of the outer face of the collar and 90 being provided with an opening through which the spindle projects, the spring being tensioned and positioned to hold the edge of the opening in normal engagement with the spindle with the spring inclined 95 outwardly from the point at which it is secured.

In testimony whereof I have signed my name to this specification.

EDWIN W. SMITH.
